UNITED STATES PATENT OFFICE.

MAUD I. BOLTZ, OF POTTSVILLE, PENNSYLVANIA.

UNDERGARMENT.

1,277,841.

Specification of Letters Patent.

Patented Sept. 3, 1918.

Application filed August 9, 1917. Serial No. 185,301.

To all whom it may concern:

Be it known that I, MAUD I. BOLTZ, a citizen of the United States, and a resident of Pottsville, in the county of Schuylkill and 5 State of Pennsylvania, have invented an Improvement in Undergarments, of which the following is a specification.

My present invention relates generally to women's garments, and more particularly to 10 women's under-garments, my object being the provision of an extremely simple garment of this nature, both as regards the manufacture thereof and the completed article, as well as one having the advantage in simplicity stated and further advantage in 15 comfort to the wearer.

Generally speaking, my invention proposes an under-garment consisting of but two pieces, capable of being joined by seams 20 along substantially continuous lines, and so united in the finished garment as to promote comfort in the highest degree.

In the accompanying drawings, which 25 illustrate my invention and form a part of this specification,

Figure 1 is a front elevation, illustrating my invention as applied to a union under-garment.

Fig. 2 is a horizontal section taken 30 through the body portion of the garment, substantially on line 2-2 of Fig. 1.

Fig. 3 is a similar view taken through one leg portion of the garment substantially on line 3-3 of Fig. 1.

35 Fig. 4 is a plan view of the lower portion of the garment.

Fig. 5 is a detailed perspective view of the body portion of the garment cut and incomplete.

40 Fig. 6 is a detailed perspective view of the crotch section detached.

Fig. 7 is a plan view of the crotch section shown in Fig. 6.

45 Fig. 8 is a plan view illustrating the manner in which the crotch sections are cut from the goods.

Referring now to these figures and particularly to Figs. 1, 2 and 3, my invention contemplates the provision of an undergarment which in this instance, I have shown in the form of a union garment, consisting 50 of a tubular body portion 10, which in manufacture is placed flatwise in one position and cut at its upper and lower portions, as seen respectively at 11 and 12 in Fig. 5, to form at the upper portion of the body 10, the

shoulder straps 13, and the suitably shaped front and back neck portions, the latter of which and the outer portions of the straps 13, are suitably finished thereafter, either 60 with or without desired trimming.

The cutting at the lower portion of the body 10, is in the nature of diametrically opposed slits extending from the lower end of the body and upwardly for a suitable distance, depending to some extent at least upon the size of the finished garment, these slits being in the first instance made at the sides of the body which when partly turned present themselves at the front and the rear 70 as at 12 in Fig. 5, so as to result in a substantial bifurcation of the lower portion of the body 10, the purpose of which will be presently described.

To the free edges around the lower slit 12 75 of the body 10, are suitably attached the side edges 14 of an inserted section 15 of hour glass form as seen particularly in Figs. 4, 6 and 7, each inserted section 15 being in one piece and preferably cut from a tubular section 16, as in Fig. 8, by means of patterns 17 laid at opposite sides thereof, and each of the shape of one-half of the section, so that when cut, each section will have the form above stated and plainly seen in Figs. 4 85 and 7.

It is to be observed, therefore, that the inserted section 15 co-operates with the bifurcated lower portion of the tubular body 10, when connected thereto, in such manner as 90 to form the complete leg portions 18 of Fig. 1, and that the seams 19 necessary for the joining of the inserted sections in place are each continuous if not in a wholly straight line, thus making the assembly of the parts 95 ready and simple operations aside from any trimming, as before stated, around the neck and arm-holes, and as seen at 20, around the extremities of the leg portions 18, which trimming is, of course, incident to every 100 garment of this nature, where its presence is desired.

It is also to be observed that in view of the particular construction presented by my invention, the intermediate portion of the inserted section 15 covers substantially the entire crotch area, and being without seams, is well calculated to promote ease and comfort in use.

Thus, in addition to the fact of advantage 110 to the manufacturer in the use of but two pieces going into the make-up of the gar-

ment, the completed article professes considerable advantage to the wearer in its use.

By referring to Fig. 2, the tubular construction of the body portion 10 may be readily seen, the difference between this construction and the construction of the leg portions 18, may be readily observed by comparison of this figure with Fig. 3, which latter includes the two seams 19, necessary for 10 the joining of the inserted section 15.

It is furthermore obvious that while I have shown in this instance, my invention in connection with a union garment, it may with equal facility be utilized in connection 15 with the manufacture of drawers alone.

I claim:

1. The method herein described of manufacturing an undergarment, said method consisting in first preparing a seamless tubular web, then centrally slitting the lower portion of said tubular web at front and rear to form divergent legs open on their inner sides, then preparing a flat web of hour-glass shape having a length twice that of 25 the slitted portion of the tubular web and a width in its narrowest portion sufficient to bridge the crotch from front to rear, then doubling said flat web at the center of its length, and then securing the opposite edges 30 of one end of said flat web to the front and rear edges of the slitted portion of one leg

of the body web and the opposite edges of the other end of said flat web to the corresponding edges of the opposite leg of the body web whereby the narrower central portion of the flat web constitutes the closed and seamless crotch of the finished garment and the wider end portions of said web constitute gussets on the inner side of the legs and widen the latter toward the bottom, the 40 seams between the two webs extending along the front and rear sides of the legs and across the body in front and back of the crotch.

2. An undergarment comprising a body 45 portion having divergent leg portions and a folded hour-glass shaped single flat web having a central portion of a width sufficient to bridge the crotch of the garment from front to rear, said flat web having the opposite 50 edges of one end united to the front and rear edges of one of the leg portions, and the opposite edges of its other end united to the corresponding edges of the other leg portion, and its narrower central portion united to 55 the body portion in front and rear of the crotch whereby the central portion of the crotch is without seam.

MAUD I. BOLTZ.
